UNITED STATES PATENT OFFICE.

ROSTO ELLSWORTH COLTON, OF EASTHAMPTON, MASSACHUSETTS, ASSIGNOR TO
WALTER W. SLACK, OF SPRINGFIELD, MASSACHUSETTS.

STEEL-CUTTING MACHINE.

1,195,184.

Specification of Letters Patent. Patented Aug. 22, 1916.

Application filed August 27, 1908, Serial No. 450,479. Renewed March 29, 1911. Serial No. 617,737.

To all whom it may concern:

Be it known that I, ROSTO E. COLTON, a citizen of the United States, residing at Easthampton, in the county of Hampshire 5 and State of Massachusetts, have invented certain new and useful Improvements in Steel-Cutting Machines; and I do declare the following to be a full, clear, and exact description of the invention, such as will enable others skilled in the art to which it 10 pertains to make and use the same.

This invention relates to improvements in steel cutting machines.

The object of the invention is to provide 15 means whereby the steel to be cut is securely clamped onto the supporting table of the machine, and means whereby the table is moved to bring the steel into engagement with the cutting wheel.

20 With this and other objects in view, the invention consists of certain novel features of construction, combinations and arrangements of parts as will be described and particularly pointed out in the appended claims.

25 In the accompanying drawings, Figure 1 is a front elevation of a steel cutting machine, showing my invention applied thereto; Fig. 2 is a side view of the same; Fig. 3 is a top plan view; Fig. 4 is a bottom plan view of the table, with the steel clamping device removed; Fig. 5 is a vertical cross sectional view of the table and the steel clamping device; Fig. 6 is a detail view of the clamp operating plate; Fig. 7 is a detail vertical sectional view through the gage clamping device, and a portion of the table; and Fig. 8 is a similar view of one of the gage clamping washers.

30 Referring more particularly to the drawings, 1 denotes the cutting machine, which consists of a base, 2, on the upper end of which are bolted or otherwise secured bearing standards, 3, in which is revolvably mounted a disk-operating shaft, 4, on which, 35 between the standards, 3, is arranged a drive pulley, 5, to receive a driving belt whereby the shaft is operated. On one end of the shaft, 4, is fixedly mounted a cutting wheel, 6, which may be of any desired construction, 40 and which may, if desired, be provided with a suitable casing, 7.

45 Pivottally mounted on suitable stud shafts, 8, on the opposite sides of the base, 2, adjacent to its lower end, are upwardly projecting table-supporting arms, 9, the upper ends

of which are bolted or otherwise secured to apertured ears, 10, formed on the lower side of a work supporting table, 12. Pivottally mounted on the front side of the base, 2, adjacent to one side thereof, is a table-operating lever, 13, the lower end of which is loosely connected to the adjacent table supporting arm, 9, by means of a link, 14, said link being connected at one end to said arm, and adjustably connected at its other end to 60 the operating lever by a bolt 15, which is engaged with one of a series of holes, 16, formed in said arm and lever.

65 On the table, 12, is arranged a central longitudinally - disposed, upwardly - projecting rib, 17, which is adapted to co-act with work-clamping devices whereby the steel or other metal to be cut is securely held in position on the table while being severed by the cutting wheel, 6. The work-clamping devices comprise a clamping-head, 18, having a vertical work-engaging face or edge, 19, and provided on its lower edge with a depending 70 guide lug, 20, and a retracting pin, 21. The clamping head, 18, is slidably engaged with 75 the upper side of the table over a slot, 22, formed in the latter and through which projects the guide lug, 20, on the lower side of said head, as clearly shown in Fig. 5 of the drawing. The head, 18, is provided with a 80 vertical bolt hole or passage 23 in which is arranged a fastening bolt, 24, the lower end of which extends through one of a number of suitable apertures, 25, in a clamp-operating plate, 26, which is slidably mounted on 85 the lower side of the table, as shown. The apertures, 25, in the plate 26 are arranged in connected pairs, the fastening bolt, 24, being engaged with one of the apertures of one pair while the retracting pin, 21, is engaged with the corresponding aperture of another pair, thus providing means for moving and for securely fastening the head in its adjusted position. The apertures 25 are 90 arranged as shown in order to obtain a fine 100 adjustment without the liability of the parts slipping as with slots.

95 The head, 18, is adapted for engagement with a bar of steel or other metal to be cut, said bar being placed upon the table adjacent to one side of the rib, 17, and is securely clamped into engagement with said rib by means of the clamping head, 18. The head, 18, is drawn into engagement with the bar of steel by means of the clamp operating 105 110

plate 26, said plate being actuated by means of a lever, 27, which is provided with a cam operating head, 28, pivoted on the table by means of a pivot bolt, 29 which passes through a slot, 30, in the table and through an aperture, 31, in the operating plate 26, and holds said lever in such a position that when the lever is turned in the proper direction the cam head 28 will engage the adjacent side of the rib, 17, which action will move the bolt, 29, and thereby the operating plate, 26, to cause the latter to draw the clamping head, 18, into engagement with the bar of steel or other work, thus clamping the latter tightly against the rib, 17, on the table. After the steel bar or other work has thus been clamped in position on the table, the latter is moved by the lever, 13, and arms, 9, to bring the steel bar into engagement with the cutting wheel, whereby a section of the bar is cut off. When the bar has thus been cut and it is desired to release the same for further adjustment, the cam lever 27 is operated to disengage the head 28 from the rib 17, thus releasing the operating plate, after which said plate and the clamping head are retracted and the head disengaged from the bar of steel by means of a retracting spring, 32, one end of which is suitably secured to the lower side of the table, while its opposite end is slightly curved and engages the lower projecting end of the retracting pin, 21, which projects downwardly from the clamping head, 18.

In order to provide for cutting off equal lengths of steel from the steel bar, I provide a suitable gage, 33, said gage comprising a longitudinal rod, the outer end of which is bent at right-angles to form a stop, 34. The bar 33 is adjustably secured to the table by means of gage-clamping disks or washers, 35, which are arranged on a clamping bolt, 36, which projects upwardly through an aperture in the table and is adapted to receive the disk or washers which are clamped into engagement with the gage by means of a clamping nut, 37, which is screwed onto the reduced and threaded upper end of the bolt. The bolt, 36, is provided with a transversely disposed passage, 38, while the clamping disk and washers 35 have formed in their opposing faces transversely disposed grooves, 39, which, when the washers are brought together, form a passage through which and through the passage, 38, in the bolt, is inserted the inner end of the gage, 33. After the gage has been adjusted to the proper position for cutting off the desired lengths of steel, the nut, 37, is screwed down onto the bolt, 36, thus clamping the gage between the washers, 35, whereby it is securely held in its adjusted position. After each length or section of the steel bar has been cut off in the manner hereinbefore described, the bar clamping de-

vices are released and the bar moved along on the table until its end again comes into engagement with the stop, 34, on the gage, thus providing for the cutting off of equal lengths from the bar.

From the foregoing description, taken in connection with the accompanying drawing, the construction and operation of the invention will be readily understood without requiring a more extended explanation.

Various changes in the form, proportion and the minor details of construction may be resorted to without departing from the principle or sacrificing any of the advantages of the invention as defined in the appended claims.

Having thus described my invention, what I claim and desire to secure by Letters-Patent, is:

1. In a machine of the character described, a suitably driven cutting wheel, a work holding table having formed therein transversely disposed slots, a longitudinally disposed clamp engaging rib formed on the upper side of said table, a work clamping head slidably mounted on the table over said slot, means to secure said head in sliding engagement with the table, an operating plate mounted on the lower side of the table and connected to said clamping head, a cam clamping lever operatively connected to said plate whereby the latter is actuated to draw the cam head into forcible engagement with the work to be clamped, and a retracting spring adapted to be engaged with said clamping head whereby the same is retracted to an inoperative position when released by said clamping lever.

2. A steel-cutting machine comprising a base, a rotary cutter supported by said base, a work-holding table, means for securing work pieces thereon, table-supporting arms pivoted to the base and carrying the table, and an operating arm engaged with one of said supporting arms at a point nearer to its pivot than to its point of connection with the table.

3. In a machine of the character described, a suitably operated cutting member, a standard on which the same is mounted, a work-carrying table, separated, relatively springy arms pivotally connected to the standard and supporting the table in a manner such as to permit movement thereof toward and from the cutting member, and means connected with one of said arms for so moving the table.

4. In a machine of the character described, a suitably operated cutting member, a standard on which the same is mounted, a work-carrying table, arms pivotally connected to the standard and supporting the table in a manner such as to permit movement thereof toward and from the cutting member, and means for so moving the table, connected

with one of said arms at a point remote from the connection of the arm with the table, said arms being relatively long and thin so as to spring when the work is brought suddenly against the cutting member.

5. In a machine of the character described, a cutting wheel, a work-holding table having a supporting surface and a work-engaging rib, a complemental work-gripping clamp arranged to move toward and from said rib, a cam lever arranged to bear against the rib on the opposite side thereof from

said clamp, and a connection between said cam lever and clamp extending below the rib and below the work-supporting surface 15 of the table.

In testimony whereof I have hereunto set my hand in presence of two subscribing witnesses.

ROSTO ELLSWORTH COLTON.
